United States Patent Office.

GEORGE CANDEE, OF BERLIN HEIGHTS, OHIO.

Letters Patent No. 77,454, dated May 5, 1868.

IMPROVEMENT IN FEED-WATER HEATERS FOR STEAM-GENERATORS.

The Schedule referred to in these Letters Patent and making part of the same.

TO ALL WHOM IT MAY CONCERN:

Be it known that I, GEORGE CANDEE, of Berlin Heights, in the county of Erie, and State of Ohio, have invented certain new and useful Improvements in Steam-Generators and Feed-Water Heaters; and I do hereby declare that the following is a full, clear, and exact description thereof, reference being had to the accompanying drawings, and to the letters of reference marked thereon, in which—

Figure 1 is a side elevation.

Figure 2 is a sectional plan view.

Figure 3 is a plan view.

The nature of my invention consists in the construction of an improved water-heater for steam-boilers, which has for its object the economical use of fuel in the development of steam. This apparatus acts upon an entirely new principle, and greatly promotes the absorption of a far greater amount of the heat which remains in the gas after leaving the fire-chamber in the ordinary furnace for steam-boilers. The gas leaves the boiler and escapes into the flue, at a much higher degree of temperature than that to which the steam is raised.

To accomplish this result, I construct an apparatus consisting of a series of cylindrical flues, arranged hexagonally, through which the gases of combustion must pass in escaping to the smoke-stack. These flues are connected by suitable removable pipes at their ends, in such a manner that said gas in escaping pass alternately back and forth through said flues, alternately from one end to the other of the same, until it reaches the end of the last section or flue, where it escapes into the smoke-stack. The draught may be assisted by the use of any of the well-known means used for accomplishing that object in other similar cases.

These flues are each provided with a jacket, or outer cylindrical shell, which is formed of the same material and is of the same length. Their ends are connected together in such a manner that the space between the shells is water or steam-tight. This space forms a chamber around the respective flues, which is designed to receive a current of water. These chambers are connected by means of small tubes or pipes, which serve to pass the water from one chamber to the next. These chambers are connected in the same order as the flues. The tubes referred to are large enough to supply the feed to the boiler. The current of water is forced in an opposite direction to that of the gases in passing through the flues. Water is inducted by the usual force-pump, and receives the heat that remains in the passing gases. It passes them forward to the next successive chamber, where it is again brought in contact with the heated surfaces, and absorbs a still greater degree of heat than from the first; and thus it continues in its course from one chamber to the next, in succession, receiving from each an increased amount of heat as it nears the furnace, until at last it reaches the boiler in a condition little below the temperature of the steam therein generated, while the gases passing in the opposite direction lose their heat and pass off into the smoke-stack. Thus the otherwise waste heat escaping with the gases, is, by this apparatus, nearly all converted into steam.

To enable others skilled in the arts to make and use my invention, I will now proceed to describe its construction and operation.

A represents the flue through which the gases pass. There may be many smaller flues in each section, if desired.

B represents the chamber or reservoir, through which the water passes from the force-pump to the boiler.

D represents the jointure-pipes which connect the flues, as seen in the drawings. The connection may be in the order there illustrated, or in any other suitable order.

E represents the pipes which connect the chambers B. They should connect them in the same order that is observed in connecting the flues, only always so attached as to conduct the most heated water of each section into the one of next higher temperature.

F represents a valve or damper, which may be used for conducting the gases directly into the smoke-stack, when desirable to do so.

The flues are arranged hexagonally around one of their number, and are all of the same diameter. Being

placed in this position, they are banded or otherwise secured together. Thus compactness and greater retention of heat are equally secured. However, these sections may be of any number, shape, or size, and may be arranged in any order desired.

I design this form of heater as applicable to heating air for the purpose of operating caloric-engines, as to heating water for steam-engines, as the principle is the same, and the method of effecting the purpose is the same. There need be nothing more said upon this subject.

It will be readily understood that the current of air or water which is being passed through the successive chambers, passes from the temperature in the first to one of a higher temperature. Thus the fluid is constantly coming in contact with a degree of heat which is of a much higher temperature, and is thus, on philosophical principles, constantly absorbing heat in an accelerating ratio.

The magnitude of the advantages derived from the use of this simple but effective apparatus cannot be fully appreciated unless we take into account the vast amount of caloric that is constantly escaping, in the gases of combustion into the flue of the ordinary boiler, and is thus lost. It is confidently believed, from actual experiment, that ninety-five hundredths of all the heat generated is entirely lost by thus escaping. If this hypothesis, supported by experiment, is correct, then any device which is capable of converting this otherwise superfluous heat into steam must necessarily be of the greatest utility. This I fully accomplish, in this apparatus, in a cheap and effective manner.

What I claim as new, and desire to secure by Letters Patent, is—

Passing the feed-water or air through successive chambers, (heated as described,) of a lower to a higher temperature, in the manner and for the purposes herein set forth and described.
